UNITED STATES PATENT OFFICE.

HOWARD F. MAXIM, OF LOCKE MILLS, MAINE.

RAILWAY-TIE.

1,269,949.

Specification of Letters Patent. Patented June 18, 1918.

Application filed March 18, 1918. Serial No. 223,179.

To all whom it may concern:

Be it known that I, HOWARD F. MAXIM, a citizen of the United States, residing at Locke Mills, in the county of Oxford and State of Maine, have invented certain new and useful Improvements in Railway-Ties, of which the following is a specification.

This invention relates to railway ties, and more especially to those made of metal; and the object of the same is to produce a two-part tie including a base and a top plate, with mechanical means for adjusting the latter upon the former so as to straighten out the line of railway being built or to true a curve therein.

This object is accomplished by the means set forth in the following specification, and reference is made to the drawings, wherein:

20 Figure 1 is a side elevation of one of my improved ties,

Fig. 2 a plan view partly in section,

Fig. 3 a plan view of one end of the base, and

25 Figs. 4 and 5 sectional details on the lines 4-4 and 5-5 respectively of Fig. 2.

The base 1 of this improved tie may be made of malleable casting, of sheet metal, and of a single part or of a plurality of parts as desired; and its details of construction are not important further than that it should have a flat top as indicated at 2, and preferably a flat bottom 3 which rests upon the road bed, and preferably it is composed 30 of a central longitudinal upright web 4 connecting the top and bottom as best seen in Fig. 4, the same being provided with a number of transverse upright webs 5 so that the ballast of the road bed may be filled in and 35 tamped around said webs to hold the base securely in position. Its dimensions, proportions, and details are otherwise unimportant excepting as hereinafter stated.

Overlying this bed is a top plate broadly indicated by the numeral 10 preferably made of two substantially rectangular heads 11 connected by a narrow shank 12, and each head has a transverse channel 13 of a size and shape to receive the base of a rail 40 14. Through the head at both sides of the channel are formed upright holes as indicated at 15, for the passage of bolts 16 whose heads when in place overlie the base of the rail and whose shanks pass down through

these holes and receive nuts at their lower 55 ends. Thus the top plate will hold the two rails equally spaced at all times, and the spacing of course will correspond with the gage of the road being built. In the top of the base and at opposite sides of its longitudinal web 4 are formed longitudinal slots 25 coincident with the holes 15, and through whose centers the bolts 16 will extend when the parts are disposed in their normal position; and the nuts 26 of the bolts will underlie the top flange of the base as best seen in Fig. 4.

In the upper face of said base between the pairs of slots 25 is disposed a groove or channel 20 enlarged at its inner end into a 70 recess 21 as best seen in Figs. 3 and 5, the side walls of said recess having notches 22 at its inner end for the reception of an upright plate 23 which may be dropped into them when the top plate 10 is removed. The 75 numeral 27 designates a shaft lying in said channel or groove 20, its outer end projecting beyond the base and squared or otherwise made angular as at 28 for the reception of a wrench or key, and its inner end threaded 80 as at 29 for the reception of a nut 30 which is of a size to move freely within the recess 21 as will be clearly understood. The inner extremity of this shaft is journaled in the plate 23 so that it may rotate therein and 85 in the channel without moving longitudinally in the base of the tie, and such rotation is obviously accomplished by turning the shaft by its angular outer end 28. The nut 30 rises above the upper face of the 90 base of the tie, and enters a cavity 31 in the lower face of the top plate 10 as seen only in Fig. 5, and therefore adjustment of the shaft and longitudinal movement of the nut within the recess cause a corresponding 95 longitudinal movement of the top plate 10 upon the base 1 as well be clear.

With this improved tie it is possible after the same has been set in the road bed and leveled if the track is straight or given the 100 proper pitch if the track is curved at this point, for the track layers to come later and apply the top plate and then the rails, putting in the bolts 16 and applying their nuts 26 rather loosely to hold all parts assembled and finally the rails are trued by adjustment of the shaft with a key applied at its outer end as already suggested, and then

the nuts 26 on the lower ends of the bolts 16 are set up tight to hold the top plate and all parts in their adjusted positions.

What is claimed as new is:—

- 5 1. A railway tie comprising a base consisting of a top, a bottom, an upright web connecting them, and transverse webs also connecting said top and bottom, the top having pairs of longitudinal slots near each end 10 on opposite sides of the longitudinal web; and a top plate overlying said base and provided with rail-channels across its upper face near its ends and with upright bolt-holes at opposite sides of each channel 15 adapted to come opposite the slots in the base.
  2. In a railway tie, the combination with a skeleton base having a flat top and near each end of the same two pairs of longitudinal slots; of a top plate overlying said top and having near each end a transverse rail-channel with upright bolt-holes on opposite sides thereof adapted to register with said slots, and bolts engaging said holes and 25 slots.
  3. In a railway tie, the combination with a skeleton base having a flat top and near each end of the same two pairs of longitudinal slots; of a top plate overlying said top 30 and having near each end a transverse rail-channel with upright bolt-holes on opposite sides thereof adapted to register with said slots, bolts engaging said holes and slots, and mechanical means for adjusting the top plate longitudinally on the base before the 35 nuts on the bolts are set up.
  4. In a railway tie, the combination with a skeleton base having a flat top and near each end of the same two pairs of longitudinal slots; of a top plate overlying said top 40 and having near each end a transverse rail-channel with upright bolt-holes on opposite sides thereof adapted to register with said slots, bolts engaging said holes and slots, a longitudinal shaft rotatably mounted within 45 the base and screw threaded at its inner end, an element connected with said top plate and engaging said screw threads, and means for turning the shaft from its outer end.
  5. In a railway tie, the combination with a skeleton base having a flat top and near each end of the same two pairs of longitudinal 50
- nal slots; of a top plate overlying said top and having near each end a transverse rail-channel with upright bolt-holes on opposite 55 sides thereof adapted to register with said slots, bolts engaging said holes and slots, the top of said base near one end being provided with a longitudinal channel enlarged at its inner end into a recess, a longitudinal shaft 60 rotatably mounted in said channel and having its inner end threaded with said recess and its inner extremity rotatably connected with the base and its outer end squared, and a nut engaging said threaded portion and 65 slidable within the recess, the upper portion of the nut engaging said top plate, for the purpose set forth.
6. In a railway tie, the combination with a base having a flat top and in one end of 70 the latter a longitudinal channel enlarged at its inner extremity into a recess, a shaft rotatably mounted in said channel and having its inner extremity threaded within said recess, and a nut engaging said threaded extremity and movable within the recess; of a top plate overlying the base and having a cavity in its under face removably engaging the nut, means on its upper face for the attachment of rails thereto, and means for 75 fastening the top plate to the base after the adjustment of the former.
7. In a railway tie, the combination with a base having a flat upper face and at each end thereof a longitudinal channel, a recess 80 at the inner end of the latter and side notches at the inner extremities of the recess; of a shaft rotatably mounted in said channel, threaded at its inner portion within said recess and squared at its outer end, 85 a plate engaging said notches and within which the inner extremity of the shaft is journaled, a nut mounted on said threaded portion and movable in said recess, a rail-carrying plate overlying said base and having a cavity with which said nut removably 90 engages, and means for fastening said plate to the base after adjustment.
- In testimony whereof I affix my signature in presence of two witnesses.
- HOWARD F. MAXIM.
